UNITED STATES PATENT OFFICE

SALVATORE A. BARONE, OF WOODSIDE, AND SAMUEL ISLER, OF WEST BRIGHTON, NEW YORK, ASSIGNEES, BY MESNE ASSIGNMENTS, TO FEDERAL TELEGRAPH COMPANY, A CORPORATION OF CALIFORNIA

ELECTRICAL CONDENSER

Application filed June 30, 1927. Serial No. 202,527.

Our invention relates broadly to electrical condensers, and more particularly to electrical condensers of the fixed type having means for effecting vernier adjustment of the capacity for accurately adjusting an associated electrical circuit. 55

One of the objects of our invention is to provide means for compensating for differences of capacity in electrical circuits by varying within close limits the electrical capacity of the condenser. 60

Another object of our invention is to provide an attachment for electrical condensers of fixed capacity whereby the capacity thereof may be changed in sufficient amounts to accurately adjust an electrical circuit in which the condenser is connected. 65

Still another object of our invention is to provide a construction of adjustable plate which may be readily applied to a fixed condenser of the stack type for varying the electrical capacity of the condenser within predetermined amounts. 70

A still further object of our invention is to provide an attachment and screw-adjusting device for application to fixed electrical condensers of standard construction for increasing the electrical capacity thereof by variable amounts whereby the capacity of a number of electrical circuits may be accurately adjusted with respect to each other. 75

Other and further objects of our invention will be understood from the specification hereinafter following by reference to the accompanying drawings, in which: 80

Figure 1 shows a condenser constructed in accordance with the principles of our invention; Fig. 2 is a plan view of a condenser embodying the principle of our invention; Fig. 3 is a cross-sectional view through the condenser construction of our invention on line 3-3 of Fig. 2; Fig. 4 is a lateral cross-sectional view through the condenser construction on line 4-4 of Fig. 3; Fig. 5 is a cross-sectional view of the condenser construction along line 5-5 of Fig. 3; Fig. 6 is a theoretical view showing the principle involved in the condenser construction of our invention; Fig. 7 is a side elevation of a modified construction of condenser constructed in accordance 90

with our invention; and Figs. 8, 9 and 10 are views of the modified construction of condenser illustrated in Fig. 7 showing more clearly the details of construction thereof. 95

In the construction of wired radio receiving apparatus where a plurality of carrier frequencies are transmitted over a line wire circuit for broadcasting entertainment programs to wired radio subscriber stations, we have found difficulty in selecting standard fixed condenser units of proper capacity for accurately adjusting the circuits of the wired radio receiver to the frequency of the carrier current channel. In a wired radio receiver it is generally necessary to employ a plurality of tuned circuits in which the standard fixed condensers available on the market are connected. We have found that it is practically impossible to manufacture fixed condensers in a large production program of sufficiently accurate values as to enable the exact frequency adjustment of each circuit of the chain of tuned circuits to be made. While it is possible to select fixed condenser units of the required capacities out of a large number of units, it is not practicable to do this. Accordingly, we have provided means which may be attached to standard fixed condensers available on the market for introducing sufficient variability to permit associated circuits to be accurately adjusted in capacity value. 100

We provide a resilient plate member which may be attached adjacent one end of the condenser stack and spatially adjusted with respect thereto for securing a vernier control of the capacity of the condenser. We may carry out our invention in a number of different ways, two of which have been illustrated in the attached drawings, and we desire that it be understood that various constructions may be employed and that no limitations upon the invention are intended. 105

Referring to the drawings in more detail, reference character 1 illustrates a condenser stack having insulated plates 2 and 3 at the opposite ends thereof with eyelet terminals 4 and 5 connected to opposite sides of the condenser. A clamp member 6 is provided around the stack 1 and end plates 2 and 3 for securing the stack under pressure. The 110

eyelet terminals 4 and 5 which pass through the insulated plate 3 also secure angle members 7 and 8 over the ends of insulated plate 2 for imparting pressure to the stack 1. The construction just described is the usual construction of standard fixed condensers available on the market. Our invention contemplates the connection of the pressure clamp 6 with one side of the condenser, that is, by means of lead 10 which connects the eyelet 4, thus tying in the clamp as one plate of the electrical condenser. An insulation sheet 9 is then placed over the clamp 6 and extends over the angle members 7 and 8. The insulated sheet 9 is secured in position by means of a bolt member 11 which passes through eyelet 5 having a retaining head 12 for enabling the bolt member 11 to be maintained in a vertical position by means of lock nut 14. The bolt member 11 passes directly through the insulated sheet 9. A resilient plate member 15 is secured over the bolt member 11 with a laminated spring device 16 in engagement therewith, the assembly being locked in position by means of nut 17 secured on the bolt member 11. This assembly enables the plate member 15 to be moved in the nature of a hinge about the bolt member 11 as a pivot, and inasmuch as the bolt member 11 is tied into the electrical condenser circuit by means of eyelet 5 there will be a change in capacity across the terminals of the condenser by a change in spacial relation of the resilient plate 15 with respect to the clamp 6. 35 This variation is brought about by means of screw 18 which works into screw-threaded portion 19 of plate 15. A nut 20 is provided for locking the screw 18 in a selected position. Contact between the screw 18 and the opposite side of the condenser is prevented by means of an insulated bushing 20 having a socket 21 which receives the end of the screw 18.

The operation of the condenser capacity change device is shown more clearly in Fig. 6 where a condenser stack is illustrated as consisting of alternate conductive and insulated sheets where the movable auxiliary plate 15 is connected to the set of stationary plates 22 and may be changed in position with respect to the set of stationary plates 23 for effecting minute changes in capacity value.

In the arrangement thus far described it will be observed that the auxiliary plate is connected with the fixed condenser at the same end at which it is mechanically mounted on the fixed condenser. In Figs. 7 to 10 we have illustrated a construction where the variable plate is connected with the fixed condenser stack adjacent its extreme outer end at the end which is spacially related to the condenser stack. We accomplish this by providing a screw, as represented at 25, having a head 24 by which the screw is secured to the fixed condenser through eyelet 4. The

screw 25 is secured in the fixed condenser by means of nut 26, and a nut 27 is arranged on the screw 25 for controlling the position of the resilient plate 28. The plate 28 is confined at its opposite end adjacent the fixed condenser stack by means of a clamp 29 which encircles the fixed condenser. It will be observed that the clamp 6 is in this arrangement connected with the eyelet 5 through a lead 30.

It should be understood that it is not necessary to employ the clamp 6 as part of a fixed condenser construction for the spacially adjustable plate may be moved with respect to one of the plates in the fixed condenser stack. Furthermore, various methods of positioning the movable plate with respect to the condenser stack may be employed, and we intend no limitations upon the arrangement other than are imposed by the scope of the appended claims.

What we claim as new and desire to secure by Letters Patent of the United States is as follows:

1. A device for attachment to a fixed electrical condenser comprising a resilient plate member, means for mechanically securing one end of said resilient plate member adjacent one of the terminals of the fixed electrical condenser, and means for changing the spacial relationship of the opposite end of said resilient plate member with respect to said fixed electrical condenser, said resilient plate member being electrically connected to one set of plates of said condenser.

2. A device for attachment to a fixed electrical condenser comprising in combination a flexible metallic plate member, means for securing one end of said plate member into mechanical engagement with said fixed electrical condenser, and means for changing the spacial relationship of the other end of said flexible plate member and said fixed electrical condenser for varying the electrical capacity across said fixed electrical condenser within predetermined limits.

3. A device for attachment to a fixed electrical condenser comprising a metallic plate member arranged to be flexed intermediate its ends, means for securing one end of said plate member into mechanical engagement with said fixed electrical condenser and establishing electrical connection between said plate member and one side of said fixed electrical condenser, and means for spacially adjusting the position of the opposite end of said plate member with respect to the opposite end of said fixed electrical condenser.

4. An attachment for fixed electrical condensers comprising a flexible metallic sheet member, an adjusting screw carried by one end of said flexible metallic sheet member, and means carried by the other end of said flexible sheet member for mechanically securing said sheet member to said fixed condenser, said screw member being arranged to

bear upon said fixed electrical condenser for varying the spacial relationship of said plate member with respect to said fixed electrical condenser, said sheet member being electrically connected to one set of plates of said condenser.

5. An attachment for fixed electrical condensers comprising in combination with a fixed condenser of the stack type having a pair of eyelet terminals at opposite ends thereof, an auxiliary plate arranged to be secured at one end to one of said eyelet terminals and arranged to be adjusted in spacial relation at its opposite end with respect to the other of said eyelet terminals for varying the electrical capacity of said condenser within predetermined limits.

10. An attachment for fixed electrical condensers comprising in combination with a fixed condenser of the stack type having a pair of eyelet terminals at opposite ends thereof, a flexible plate member having means for securing one end thereof with respect to one of said eyelet terminals in electrical connection with one side of said electrical condenser, an insulated bushing arranged to be secured in the other of said eyelet terminals, and a screw member carried by said plate member and arranged to engage said insulated bushing whereby said plate member may be changed in spacial relationship with respect to the stack of said fixed electrical condenser for shifting the electrical capacity thereof within predetermined limits.

15. An attachment for fixed electrical condensers comprising in combination with a fixed condenser of the stack type having a pair of eyelet terminals at opposite ends thereof, a flexible plate member having means for securing one end thereof with respect to one of said eyelet terminals in electrical connection with one side of said electrical condenser, an insulated bushing arranged to be secured in the other of said eyelet terminals, and a screw member carried by said plate member and arranged to engage said insulated bushing whereby said plate member may be changed in spacial relationship with respect to the stack of said fixed electrical condenser for shifting the electrical capacity thereof within predetermined limits.

20. An attachment for fixed electrical condensers comprising in combination with a fixed condenser of the stack type having a pair of eyelet terminals at opposite ends thereof, a flexible plate member having means for securing one end thereof with respect to one of said eyelet terminals in electrical connection with one side of said electrical condenser, an insulated bushing arranged to be secured in the other of said eyelet terminals, and a screw member carried by said plate member and arranged to engage said insulated bushing whereby said plate member may be changed in spacial relationship with respect to the stack of said fixed electrical condenser for shifting the electrical capacity thereof within predetermined limits.

25. An attachment for fixed electrical condensers comprising in combination with a fixed condenser of the stack type having a pair of eyelet terminals at opposite ends thereof, a flexible plate member having means for securing one end thereof with respect to one of said eyelet terminals in electrical connection with one side of said electrical condenser, an insulated bushing arranged to be secured in the other of said eyelet terminals, and a screw member carried by said plate member and arranged to engage said insulated bushing whereby said plate member may be changed in spacial relationship with respect to the stack of said fixed electrical condenser for shifting the electrical capacity thereof within predetermined limits.

30. An attachment for fixed electrical condensers comprising in combination with a fixed condenser of the stack type having a pair of eyelet terminals at opposite ends thereof, a flexible plate member having means for securing one end thereof with respect to one of said eyelet terminals in electrical connection with one side of said electrical condenser, an insulated bushing arranged to be secured in the other of said eyelet terminals, and a screw member carried by said plate member and arranged to engage said insulated bushing whereby said plate member may be changed in spacial relationship with respect to the stack of said fixed electrical condenser for shifting the electrical capacity thereof within predetermined limits.

35. In testimony whereof we affix our signatures.

SALVATORE A. BARONE.
SAMUEL ISLER.
